UNITED STATES PATENT OFFICE.

GEORGE F. STEEDMAN, OF ST. LOUIS, MISSOURI.

ELEVATOR-CAGE.

No. 831,248.

Specification of Letters Patent.

Patented Sept. 18, 1906.

Application filed March 12, 1906. Serial No. 305,652.

To all whom it may concern:

Be it known that I, GEORGE F. STEEDMAN, a citizen of the United States, residing at St. Louis, Missouri, have invented a certain new 5 and useful Improvement in Elevator-Cages, of which the following is a full, clear, and exact description, such as will enable others skilled in the art to which it appertains to make and use the same, reference being had 10 to the accompanying drawings, forming part of this specification, in which—

Figure 1 is a front elevation of a portion of a knockdown elevator-cage embodying the features of my invention. Fig. 2 is a side 15 elevation of the cage shown in Fig. 1. Fig. 3 is a plan view of Fig. 1. Fig. 4 is a sectional view on the line 4 4 of Fig. 1. Fig. 5 is a view, partly in section, taken on the line 5 5 of Fig. 2; and Fig. 6 is a sectional view on 20 the line 6 6 of Fig. 4.

This invention relates to elevators, and particularly to the cages of elevators.

The main object of my invention is to provide a knockdown elevator-cage—namely, 25 one that can be built complete at the factory and shipped in disassembled or “knock-down” form to the place where the elevator is to be installed, thereby obviating the necessity of employing a skilled mechanic to 30 set up the elevator-cage and insuring a low freight classification in shipment.

Another object of my invention is to provide an elevator-cage that is very rigid and comprising few parts and which can be 35 easily converted from a non-safety-device cage to a safety-device cage. The safety device is also of novel form, as well as other features which will be hereinafter pointed out.

Prior to my invention it has been the general practice to either ship the cage assembled from the factory to the place where the elevator was installed or else ship the parts of the cage and send an experienced elevator-man to put the cage together. If the cage is 45 shipped assembled, the freight-rate on the same is exceedingly high on account of the height and bulkiness of the cage, and if all of the parts are shipped disassembled and an experienced elevator-man is sent to put the 50 parts together the cost of his services enhances greatly the cost of manufacture of the elevator. My improved knockdown elevator-cage comprises very few parts—namely, a platform part, which is built at the factory 55 and shipped complete, and an upper part,

which is built at the factory and shipped complete, the upper part lying flat upon the platform part, so that the cage occupies very little space, and accordingly can be shipped at a low freight classification. When the cage arrives at the place where the elevator is to be installed, the upper part can be attached to the platform part by simply driving a few rivets, so that it is unnecessary to employ a skilled 60 mechanic to set up the cage. 65

Referring to the drawings, which represent the preferred form of my invention, 1 designates the floor of the platform, which preferably consists of wood and is supported by horizontal members 2, extending the full 70 width of the platform at the front and back, and side horizontal members 3, extending the full length of the platform. These horizontal members preferably consist of channels which are secured together in the form 75 of a rectangle, and thus a very rigid construction is produced.

I have shown only one-half of the cage in the drawings; but it will of course be understood that the other half of the cage is identical with that shown. Secured to each of the side horizontal members 3 by rivets 4 is a casting which is of novel construction and forms one of the important features of my cage. Said casting consists of ears 5, that 80 embrace the guide 6 on the elevator-frame, on which the cage travels, an upwardly-projecting portion 7, that is secured to a vertical member comprising a portion of the upper 85 part of the cage, bearings 9, which receive the rock-shafts 10, comprising part of the safety devices, and surface 11, which co-operates with buffers 12 on the elevator-frame. The upper part of the cage consists of two 90 horizontal members 13, preferably channels, which are secured by rivets 14 to castings having ears 15, which embrace the guide of the elevator-frame, said castings extending 95 between said horizontal members, as shown in dotted lines in Fig. 1. On the upper portion 100 of each of said castings is a boss 16, that receives a cylindrical buffer 17, which co-operates with a surface on the elevator-frame, and said castings are also provided with bearings 18, which receive the shafts 19, forming 105 part of the safety devices. The portion of the casting that extends between the horizontal members 13 is hollow and receives the vertical member 20, which is secured to said casting by rivets 21, as shown in dotted lines 110

in Fig. 2, the lower portion of said vertical member being secured to the upwardly-projecting portion 7 of the casting of the platform part by rivets 22, (shown in dotted lines 5 in Fig. 2,) which rivets 22 are adapted to be driven at the place where the elevator is set up.

The platform part of the cage, comprising the wooden floor, horizontal members 2, and 10 side members 3, with the castings connected thereto, is assembled at the factory, and the upper part of the cage, comprising the vertical members 20, horizontal members 13, and castings connecting them together, is assembled 15 at the factory. These two parts are placed one on top of the other for shipment and are connected together to form the complete cage by simply driving the rivets 22 as previously described. To strengthen the 20 cage, diagonal braces or cross-rods 23 and 24 are carried by the castings of the upper part of the cage and are adapted to be secured to the platform part when the cage is set up, the upper castings being provided with openings 25 through which the braces 24 extend and with ears or lugs 25, through which the braces 23 extend, and the lower castings being provided with ears 25' to receive the braces 24. Preferably, safety devices are provided at the bottom 30 of the cage, as well as at the top of the cage, so that in case the cage is provided with a heavy load and the hoisting apparatus should break said safety devices would become operative and prevent the platform 35 part of the cage from being torn away from the upper part of the cage, this being liable to occur in case the cage were provided with safety devices only at the top. The safety devices which I have herein shown consist of 40 pairs of dogs 26 and 27 at the top and bottom of the cage, respectively, said dogs being rigidly connected to the rock-shafts 19 and 10. The rock-shafts 19 are provided with arms 28, as shown in Fig. 4, which are connected 45 by links 29 to a cross-bar 30, carried by a slide 31, which is connected to the rope 32 of the hoisting apparatus. A spring 33 (shown in dotted lines in Fig. 1) is connected to the horizontal members of the upper part of the 50 cage and extends through an opening 34 in the slide 31, so that said spring is normally under compression. In case the rope of the hoisting apparatus should break, however, said spring being relieved will force the slide 55 and cross-bar downwardly, thereby rocking the shafts 19 to cause the pair of dogs 26 to engage the guide 6 of the elevator-frame. The dogs 26 are connected to the dogs 27 at the bottom of the cage by means of links 36, 60 so that said dogs will be actuated simultaneously with the upper dogs. If the cage is not provided with the safety devices when it is first installed, it is a very simple matter to add them at any time without the aid of a 65 skilled mechanic, as the castings are provided

with the bearings into which the rock-shafts can be inserted, the safety-device parts being shipped from the factory to the owner of the elevator. It is obvious that in place of the rope 32 a piston-rod of a direct-acting hoist 70 can be substituted therefor.

Having thus described the invention, what is claimed as new, and desired to be secured by Letters Patent, is—

1. A knockdown elevator-cage comprising an upper part consisting of horizontal members, two vertical members and castings permanently connecting said members together, said castings being constructed to receive said vertical members and being arranged between the horizontal members, ears on said castings for embracing the guides on the elevator-frame, and a platform part removably connected to the vertical members of the upper part; substantially as described. 80 85

2. A knockdown elevator-cage comprising an upper part consisting of horizontal members and two vertical members permanently connected together and a platform part consisting of a framework carrying a 90 floor, and castings secured to said framework and provided with portions which are adapted to be removably connected to the vertical member of the upper part, said castings having buffing-surfaces and ears which embrace 95 the guides on the frame of the elevator; substantially as described.

3. A knockdown cage consisting of an upper horizontal member to which the hoisting device is attached, vertical members, castings serving to connect the horizontal member to the vertical members and being constructed to receive said members, guide-ears on said castings, a lower platform part adapted to be connected to said vertical members 100 comprising castings having guide-ears, the upper and lower castings having bearings adapted to receive rock-shafts; substantially 105 as described.

4. A knockdown cage consisting of an upper horizontal member to which the hoisting mechanism is attached, vertical members, a lower platform part comprising a frame and adapted to be connected to the vertical members, upper castings having guide-ears and 110 bearings for rock-shafts, said castings being adapted to receive said upper horizontal member and said vertical members, and lower castings adapted to receive the frame 115 of said platform part and said vertical members, said castings having guide-ears and bearings for rock-shafts; substantially as described. 120

5. A knockdown cage consisting of an upper horizontal member to which the hoisting 125 mechanism is attached, a lower platform part, vertical members and diagonal members for connecting the upper member to said platform part, upper castings adapted to receive said horizontal, vertical and diagonal mem- 130

bers provided with guide-ears and bearings for rock-shafts, and lower castings having guide-ears and bearings for rock-shafts, said lower castings being constructed to receive the platform part, the vertical members and the diagonal members; substantially as described.

In testimony whereof I hereunto affix my signature, in the presence of two witnesses, this 5th day of March, 1906.

GEORGE F. STEEDMAN.
